UNITED STATES PATENT OFFICE.

GEORGE F. VOIGHT, OF OAKLAND, CALIFORNIA.

METAL LATH.

Application filed September 29, 1924. Serial No. 740,581.

My invention relates to improvements in metal lath particularly adapted for cooperation with the wall sheathing of stucco structures for supporting and reinforcing the stucco composition; and one of the objects thereof is the provision of elongated indentations or channels pressed into the body of the lath at right angles with its margins and extending approximately half way across the face thereof.

With the foregoing and further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a view in elevation of a section of metal lath constructed in accordance with my invention, secured to the face of the wall sheathing of a stucco structure;

Figure 2 shows a modified form of the lath and a fragmental section of wall sheathing;

Figure 3 is a detailed view of a portion of the lath attached to the wall sheathing;

Figure 4 is a sectional view through the lath, approximately on line 4'-4' of either Fig. 1, Fig. 3 or Fig. 6;

Figure 5 is a sectional view on line 5'-5', Fig. 2, an intermediate portion being broken away; and

Figure 6 shows an edge view of a portion of the lath.

Referring to the drawings in detail, throughout which like reference characters designate like parts:

The numeral 1 designates the usual wall sheathing, secured preferably in lateral close-up order across the face of the wall timbers of a structure adapted to be provided with an exterior coating of stucco composition 2.

3 designates my improved lath, which comprises upper and lower marginal wires 4, and intermediate inter-woven mesh wires 5, forming a web or body portion 6, the latter provided with upper and lower laterally spaced apart indentations 7, which embrace the shaded portions 8 of the intermediate wires 5 inside of the broken or dotted lines 9, and extend from the marginal wires 4 of

either edge of the lath to approximately the middle of the body portion, and are formed by pressing portions of said marginal wires and portions of said intermediate wires to one side out of the plane of the body portion.

The indentations 7 are adapted primarily as spacing means for holding the lath a predetermined distance outwardly from the face of the wall sheathing 1 against which they seat, thereby providing outstanding support and reinforcement for the stucco composition 2, the latter adapted to be applied by spreading it on the face of the sheathing and on and around the lath until a coating of proper thickness is obtained.

As it is desirable to have as little of the lath as possible in actual contact with the wall sheathing in order to permit relatively uninterrupted stucco contact therewith, I prefer to arcuate the indentations in cross section so that only the comparatively limited areas of the apexes thereof will engage the sheathing.

In the preferred form of the invention, indentations 7 extend from both the upper and lower marginal wires 4 laterally inwardly to a point approximately equi-distant from each, at which point they terminate (see Fig. 1), while in the modified form they begin at a point a distance inwardly from the marginal wires and terminate the same as in the preferred form, namely, approximately midway from either of said marginal wires (see Fig. 2). With the exception mentioned, namely, beginning distant from the marginal wires 4, the indentations are formed and located relative to each other the same as above set forth for the preferred form of the invention. The modified form may possess some advantages over the preferred form where it is desired to over-lap the edges of the one course of the lath over the edge of the next adjoining course above or below. The marginal wires 4 in the modified form not being crimped in forming the indentations, permit of relatively close engagement with the adjoining course when overlapping it.

The broken lines 10 illustrate the approximate curvature of the inner ends of the indentations of the preferred form, and of both the inner and outer ends of the modified form of the invention.

In both of said forms of the invention, the indentations of one edge of the lath are

intended to be disposed in staggered relation to the indentations of the other edge, whereby the axes of one set or series thereof will extend approximately equi-distant between, and parallel with, the indentations of the other set (see Fig. 1).

Commercial metal lath is usually manufactured in sheets 36 inches wide and from 25 feet to 50 feet long, and as such is rolled 10 into tightly coiled bundles for purposes of transportation, and I have found by experimenting that when the indentations are formed to extend all the way across the sheet, instead of terminating half way from either edge in staggered order as in the present invention, the lath when unrolled will retain more or less of the curvature of the bundle from which it was unrolled, causing it to bulge out between the indentations after its application to the wall 20 sheathing, which is objectionable, particularly to the plasterer, who finds it difficult to apply the stucco composition uniformly on bulging lath. In the present invention, however, in which the indentations are shorter and extend only half way across the sheet, and in which the lower series of indentations are arranged in staggered relation to the upper series, there is much less 30 danger of bulging of the lath between the indentations. It is also to be noted that as the lower series of indentations are disposed intermediate the upper series, they materially assist in supporting vertically 35 the stucco composition applied to the wall sheathing in the spaces intermediate the upper indentations.

As the indentations are intended primarily for spacing the lath outwardly from the 40 wall sheathing, their depth, obviously, should be equal to the distance it is desired to space the lath, which, considering the stucco to be applied to be of the usual thickness, is about $\frac{3}{8}$ of an inch; while the distance between the indentations of either series is preferably about 6 to 8 inches from "center-to-center" of indentations, depending upon the dimensions of the mesh of the lath and also on the thickness of the 50 stucco coating to be applied.

To apply my improved lath to the wall sheathing of a stucco structure, it is simply necessary to stretch the lath longitudinally horizontally across the sheathing, with the 55 indentations seating against the face thereof (see Fig. 1), and drive ordinary nails 11 at suitable intervals through the indentations part way into the sheathing and then bend them over against the lath for binding the sheathing thereagainst, and like 60 nails through the lath intermediate the indentations, the latter nails to be driven part way into the sheathing and then bent over against the lath at a distance outwardly from said sheathing, for securing 65

the lath thereto at said distance outwardly therefrom. The latter nails are adapted both for assisting the former mentioned nails in securing the wall sheathing and for assisting the lath in supporting the stucco 70 applied against the sheathing intermediate the indentations. Any number of nails may be employed for attaching the lath or for supporting the stucco composition.

While fastening means other than the 75 nails 11 may be employed for attaching the lath to the wall sheathing, such, for instance, as staples or the like, I prefer to use the nails for the reason that they are less expensive, are more readily manipulated 80 preparatorily to driving, are easier driven, and may be employed advantageously as levers for stretching the lath laterally in any direction if it is desired to do so.

It is to be understood that I do not desire to limit myself to the particular type 85 of woven wire lath shown and described in the present application, but on the contrary the lath may comprise any suitable form of "mesh" fabric, including that commonly known as "poultry netting", or such metal lath known as "expanded metal lath", or the like.

It is further to be understood that "building paper" may be applied to the face of 90 the wall sheathing before the application of the lath or stucco composition; and, as such paper when so applied may be considered to form a portion of such sheathing, the designation "wall sheathing" or "sheathing" as used in this specification shall include such paper.

I claim:

1. In lath of the character described, a 100 body portion having a plurality of indentations pressed thereinto from one side and extending from one edge thereof to approximately the center thereof, where they terminate.

2. In lath of the character described, a 110 body portion having a plurality of indentations pressed thereinto at intervals and extending from one of its margins laterally inwardly and terminating substantially inwardly from the opposite margin.

3. In lath of the character described, a 120 body portion having a plurality of elongated indentations pressed thereinto at regular intervals from one side, said indentations intersecting with one of the margins of the lath and extending from said margin inwardly at right angles therewith but terminating short of the opposite margin.

4. In lath of the character described, a 125 body portion having an elongated indentation formed therein and extending from one of its margins a distance inwardly but terminating short of the opposite margin, and a second indentation formed in said body portion and extending from said op- 130

- posite margin a distance inwardly but terminating short of said first named margin, the axes of said indentations extending parallel with each other.
5. In lath of the character described, a body portion having a plurality of elongated indentations formed therein, a division of said indentations extending from its upper margin at right angles inwardly 10 and terminating approximately midway of said body portion, the other division of said indentations extending from the lower margin of said body portion at right angles upwardly and terminating approximately 15 midway thereacross, said indentations disposed at regularly spaced apart intervals and in such relative order that the axes of the indentations of one of said divisions extend between and parallel with the axes 20 of the other division of said indentations.

6. Metal lath of the character described,

comprising, a body portion having upper and lower marginal wires, said body portion having a plurality of laterally spaced elongated indentations pressed therein from 25 one side, opposed ends of said indentations disposed in parallel planes, one of said planes extending between said marginal wires and parallel therewith.

7. In metal lath of the character described, 30 a body portion having upper and lower marginal wires, an elongated indentation formed in said body portion, the axis of said indentation extending at an angle with the axis of said body portion, one end of 35 said indentation terminating intermediate said marginal wires.

In testimony of the foregoing being my own, I have hereunto affixed my signature this 22nd day of September, 1924.

GEORGE F. VOIGHT.
